CALENDAR PAD BASE

Frank Bartuska, New York, N. Y., assignor to Wilson Jones Company, Chicago, Ill., a corporation of Massachusetts

Application March 18, 1957, Serial No. 45,301

Term of patent 14 years

(Cl. D74—5)

Fig. 1

Fig. 2

Fig. 3

Fig. 4

Figure 1 is a top plan view of a calendar pad base showing my new design;

Figure 2 is a side elevation thereof;

Figure 3 is a rear elevation thereof; and

Figure 4 is a front elevation thereof.

The broken line showing of the calendar pad is for illustrative purposes only.

I claim:

The ornamental design for a calendar pad base, as shown and described.
